TONGS

Harvey R. Hansen, Jr., Detroit, Mich.

Application July 28, 1947, Serial No. 764,178

4 Claims. (Cl. 294—118)

1

This invention relates generally to gripping devices of the type employed to hold an object while the latter is being raised or transported and refers more particularly to improvements in tongs.

One of the objects of this invention is to provide a gripping device comprising tongs having reliable means for firmly gripping an object and having readily operable means for quickly releasing the object when desired.

A more detail object of this invention is to provide tongs having arms pivotally connected together adjacent the upper ends for relative swinging movement and having gripping dogs respectively pivoted to the lower end portions of the arms for swinging movement from a released or inoperative position to an operative position wherein the dogs extend laterally inwardly from the arms into gripping engagement with an object between the arms.

Another feature of this invention is to provide tongs of the above type having latch means on each arm for engagement with the dog on the latter to hold the dogs in their operative or object gripping positions and having means for operating the latch means as a unit to simultaneously release both dogs from the object.

The foregoing as well as other objects will be made more apparent as this description proceeds especially when considered in connection with the accompanying drawing wherein:

Figure 1 is a side elevational view partly in section of a gripping device embodying tongs constructed in accordance with this invention and showing the gripping dogs in their operative and inoperative positions; and

Figure 2 is a fragmentary side elevational view of the tongs shown in Figure 1.

The gripping device forming the subject matter of this invention is in the form of tongs 10 comprising a pair of arms 11, a pair of gripping dogs 12 and latch elements 13 for the dogs. The upper end portions of the arms 11 cross each other and are pivotally connected by a pin 14 permitting relative swinging movement of the arms in substantially parallel planes. The extreme upper ends of the arms are connected by links 15 to a lifting chain 16 in such a manner that upward movement of the chain applies a force to the upper ends of the arms 11 in a direction to swing the lower end portions of the arms inwardly or toward each other.

The lower end of each arm 11 is bifurcated to provide a recess 17 of sufficient width to freely receive a gripping dog 12 and a latch element

2

13. The dogs 12 are pivotally connected adjacent the upper ends thereof on pins 18, respectively, extending transversely of the recesses 17 and anchored on the furcations at the lower ends 5 of the arms 11. The pins 18 extend substantially parallel to each other and to the axis of swinging movement of the arms to permit swinging movement of the dogs 12 from the released positions shown by the broken lines in Figure 1 of the drawing to the operative or gripping positions shown by the full lines in the same figure of the drawing. It will be noted that since the dogs 12 are pivoted adjacent the upper ends to the respective arms 11 the action of gravity urges 15 the dogs to their inoperative or dotted line positions shown in Figure 1 of the drawing.

The latch elements 13 are respectively pivotally mounted at their upper ends on the arms 11 by pins 19 extending transversely of the recesses 20 17 above the pins 18 and anchored on the furcations of the arms. Thus, the latch elements 13 normally extend downwardly from the pins 19 and the latter are respectively spaced laterally outwardly from the pins 18 to position the lower 25 or swinging ends of the latch elements at the laterally outer sides of the dogs 12 when the latter are in their inoperative positions. In this connection it is to be noted that the outer edges of the dogs 12 are arcuate and provide cam surfaces 20. The cam surfaces 20 respectively engage the swinging ends of the latch elements at the laterally inner sides of the elements so that as the dogs 12 are swung in a clockwise direction about their respective pins 18 to the operative 30 positions shown in Figure 1 of the drawing, the latch elements 13 are swung outwardly by the cam surfaces 20 on the dogs to clear the upper ends of the dogs. As soon as the upper ends of the dogs 12 clear the lower ends of the latch elements 13, the latter return by the action of gravity to their latched positions wherein the lower ends of the latch elements are positioned to respectively engage the inner edges of the upper ends of the dogs and hold the latter in their 35 operative positions.

When the dogs 12 are held in their operative positions by the latch elements 13, the lower ends of the dogs project laterally inwardly from the lower ends of the arms 11 and cooperate with 40 one another to grip an object 21 such, for example, as a log between the arms 11. It will be noted from Figure 1 of the drawing that when an object is gripped by the dogs the force applied to the dogs by the weight of the object is transmitted directly to the pins 19 through the latch

elements and accidental release of the dogs from the object is prevented. It will further be noted from Figure 1 of the drawing that pins or stops 22 are respectively secured to the lower ends of the arms in positions to limit the extent of swinging movement of the dogs 12 to their operative positions.

The dogs 12 remain in their operative positions until the latch elements 13 are swung upwardly and outwardly out of the path of travel of the upper ends of the dogs. This is accomplished by providing a cable 23 having the opposite ends respectively connected to the swinging ends of the latch elements at the laterally outer sides thereof. The ends of the cable are passed upwardly over pins 24 and through suitable guides 25 secured to the arms 11. A suitable handle 26 is secured to the cable 23 intermediate the ends thereof in a position to enable the same to be readily gripped by the operator. The construction is such that a downward pull on the cable intermediate the ends thereof simultaneously swings the latch elements 13 outwardly to their released positions against the pins 24. When in this position the dogs are released from the latch elements and are free to swing in a counter-clockwise direction to release the object gripped thereby.

What I claim as my invention is:

1. A device for gripping objects, comprising tongs having a pair of arms pivotally connected together adjacent the upper ends thereof for swinging movement toward and away from each other, a pair of dogs respectively pivotally connected intermediate the ends thereof on the lower end portions of the arms, a gripping portion on each dog at one side of the pivot axis thereof and a latch engaging part on each dog at the opposite side of said pivot axis, a pair of latch elements having the upper ends respectively pivotally supported on the arms at points spaced above the dogs and having the lower end portions engageable with the latch engaging surfaces on the dogs to locate the gripping portions of the dogs in positions to grip an object located between the arms, and selectively operable means connected to the swinging ends of the latch elements for simultaneously swinging the latch elements outwardly to release the dogs.

2. A device for gripping objects, comprising tongs having a pair of arms pivotally connected together at the upper ends thereof for swinging movement toward and away from one another, a pair of dogs respectively pivotally connected intermediate the ends thereof on the lower end portions of the arms, a gripping portion on each dog at one side of the pivot axis and a latch engaging part on each dog at the opposite side of the pivot axis, said dogs being normally urged to positions wherein the gripping portions thereof extend in a downward direction from the pivot axes, a pair of latch elements having the upper ends respectively pivotally supported on the arms at points spaced above the dogs and having the lower end portions respectively engageable with the latch surfaces on the dogs to hold the latter in positions wherein the gripping portions project inwardly with respect to the arms, a flexible linear member having the opposite ends respectively connected to the lower ends of the latch elements at the outer edges thereof and extending upwardly along the respective arms and having an intermediate portion acces-

sible for manipulation to simultaneously swing the latch elements out of engagement with the dogs.

3. A device for gripping objects, comprising tongs having a pair of arms pivotally connected together adjacent the upper ends thereof for swinging movement toward and away from each other, a pair of dogs respectively pivotally connected intermediate the ends to the lower end portions of the arms, a gripping portion on each dog at one side of the pivot axis and a latch engaging part on each dog at the opposite side of the pivot axis, said dogs being normally urged to positions wherein the gripping portions extend in a downward direction from the pivot axes, a pair of latch elements having the upper ends respectively pivotally connected to the arms at points spaced above the dogs and having the lower swinging ends extending downwardly to positions adjacent the outer edges of the dogs whereby inward swinging movement of the dogs to their object gripping positions engages the outer edges of said dogs with the lower swinging ends of the latch elements and cams the lower ends of the latch elements into engagement with the latch engaging parts on the dogs to latch the latter in their object gripping positions, and means for selectively swinging the latch elements outwardly to release the same from said dogs.

4. A device for gripping objects, comprising tongs having a pair of arms pivotally connected together adjacent the upper ends thereof for swinging movement toward and away from each other, a pair of dogs respectively pivotally connected intermediate the ends to the lower end portions of the arms, a gripping portion on each dog at one side of the pivot axis and a latch engaging part on each dog at the opposite side of the pivot axis, said dogs being normally urged to positions wherein the gripping portions extend in a downward direction from the pivot axes and having arcuate cam surfaces at the outer edges thereof, a pair of latch elements having the upper ends respectively pivotally connected to the arms at points spaced above the dogs and having the lower ends extending downwardly to positions adjacent the cam surfaces at the outer edges of the dogs whereby inward swinging movement of the dogs to their object gripping positions engages the cam surfaces on the dogs with the lower ends of the latch elements and swings the latter outwardly sufficiently to enable the latch engaging surfaces on the dogs to assume positions below the lower ends of the latch elements, the location of the pivot axes of the latch elements with respect to the pivot axes of the dogs being such that the lower ends of the latch elements are normally positioned to engage the latch surfaces on the dogs, and a flexible linear member connected to the lower ends of both latch elements for simultaneously swinging the latter outwardly to release the dogs.
